KENTUCKY

OPHTHALMIC LENS

Application filed September 27, 1928. Serial No. 308,721.

This invention relates to ophthalmic blanks and lenses and has for an object the provision of a lens with a plurality of focal powers.

5 Another object is to provide an ophthalmic lens blank of the type referred to which is simpler and less expensive to manufacture than heretofore known lenses for such purposes.

10 Another object is to provide an ophthalmic lens blank for the purposes stated which is adapted to be ground on any curve or combination of curves which may be required for a given correction.

15 Another object is to provide a fused blank for ophthalmic lenses wherein the likelihood of disturbing elements in the lens due to the fusing process is reduced to a negligible amount.

20 Another object is to provide a means and method for making a fused lens providing portions of different power and wherein the joinder or fusion of said portions is practically invisible.

25 These and other objects are attained by the method set forth and the means described herein and shown in the accompanying drawings, in which:

30 Fig. 1 is a cross sectional view of the elements going into the preparation of a part of the lens of the invention.

Fig. 2 is a cross sectional view of such part after preparation and prior to grinding.

35 Fig. 3 is a cross sectional view of a part forming a detail of the invention.

Fig. 4 is the fragmental cross sectional view of a lens blank ground to receive the part shown in Fig. 3.

40 Fig. 5 is a cross sectional view of the completed blank, part being broken away.

Fig. 6 is a view of a completed lens formed from a lens blank such as is shown in Fig. 5.

45 Fig. 7 is an enlarged cross sectional view taken on line 7—7 of Fig. 6.

The ophthalmic lens of the invention comprises a specially prepared button or disk, indicated generally as 10, as is shown in 50 cross section in Fig. 3 and a lens blank 11

to which the prepared button is fused in the manner usually employed in the manufacture of Kryptok blanks. It is to be noted particularly that the blank 11 is heated but once in order to fuse the button 10 thereto and that this single heating of the large blank is highly advantageous over a plurality of fused heats to which heretofore proposed lenses have been subjected. This is true because the heat vibrations as well as possible other vibrations which occur during a second heating will very frequently set up a disturbance in the body of a large piece of glass such as the blank 11 so as to oftentimes render it highly unsuitable for use as an ophthalmic lens. It has also been observed that the liability to disturbance due to a second fusing of pieces of glass is greatly reduced as the size of the piece of glass is reduced.

Referring now to the prepared button 10 it will be noted from Fig. 1 that a small disk or block of optical glass 12 has a recess 13 ground therein into which a piece of spectacle glass 14, ground as at 15 in substantial conformity to the recess 13 is seated. These parts are shown in Fig. 1. It is to be understood that these parts are quite small. The disks or parts 12 and 14 prepared as shown in Fig. 1, are then submitted to a fusing heating to unite them so that the rough button shown in Fig. 2 results, and comprises a smaller portion 14 of ordinary spectacle glass and the larger united portion 12 of optical glass of a higher index of refraction than the part 14. The rough button shown in Fig. 2 is then ground to assume a cross sectional shape as shown in Fig. 3 and constitutes the completed prepared button 10. A full sized blank 11 of ordinary spectacle glass, similar to the portion 14, is then recessed as at 16 so as to receive the prepared button 10. The prepared button 10 and the suitably recessed spectacle blank 11 are then fused together at a single heating whereupon there is provided a commercial blank which may be ground according to the needs of a wearer, either as a spherical lens, cylindrical lens or prismatic lens or any combination of

two or all of them. This is true because the portion 12 is the optical glass of higher index of refraction and is exposed on the outer face of the lens and that the small 5 portion 14 of ordinary spectacle glass has now united with the blank 11 of similar ordinary spectacle glass and is wholly concealed and entirely invisible within the body of the completed lens. It is to be noted that 10 numerous of the proposed fused lenses providing for a plurality of focal powers or a plurality of fields of vision are practical only when they are prepared into a spherical lens so that it was necessary to sacrifice the 15 advantage of a proper correction in certain cases in order to provide for the several different fields of vision in one lens.

Referring now to Figs. 6 and 7 it will be noted that the large field 17 will be wholly 20 the ordinary spectacle glass and will constitute the large field for distant vision; the somewhat crescent shaped field 18 will be through the portion 12 or the optical glass of a higher index of refraction, the 25 power of which is increased or decreased by the grinding of the external curves on the finished lens. The field 19 is of a reduced power due to the original spherical depression 13 formed in the optical glass 30 12. This field 19 in the ophthalmic lens of the present invention may thus provide a field which is uniform with the field 17 or which may provide a field of a strength intermediate that of the reading field 18 and 35 the distance field 17. This latter arrangement is found highly desirable for those who have occupations which require looking down at their work through a field which is preferably disposed at the bottom of the 40 lens. Examples of desirable use of such a lens might be found in playing golf, where the player desires to have a very distinct view of the ball on the ground before him but finds it too far away to be properly 45 seen through the reading portion of his lens. Another use would be for the housewife in doing work which is preferably held on her lap. Particularly in ironing is the lens of the invention valuable to the housewife.

50 Thus in summarizing the advantages of the ophthalmic lens of the invention and the method of making it it will be noted that the steps of manufacture as outlined all tend to minimize to a negligible amount the imperfections attending the manufacture of heretofore proposed lenses, thus rendering the cost of manufacture as well as the care and skill in the process less expensive and difficult. The resultant blank is adapted 55 for commercial distribution as such for grinding into a finished lens by any skilled optician and according to any prescription. The most complicated of prescriptions for single piece lenses will present no difficulties 60 in grinding from the blanks of the present 65

invention. The finished lens is without disturbing elements. The joinder of parts of the lens is practically invisible, and the small lowermost field 19 is readily arranged to afford vision exactly as wanted in the most 70 desirable position in the lens without special fabrication of the rough blank. Thus the blank is capable of commercial distribution in the manner impossible with heretofore proposed lenses of the multi-focal type so 75 that a pair of spectacles of the multi-focal type may be prepared or repaired by any lens grinding optician as quickly and with no more difficulty than the same optician would prepare a simple lens. This is due 80 to the disposition of the convex curve 20 and concave curve 13 of the optical glass member 12 interiorly of the completed blank.

What is claimed is:

85 A lens blank of the class described comprising a major blank of spectacle glass countersunk eccentrically on one face and a prepared member fused into said countersunk recess, the prepared member comprising 90 a relatively large piece of optical glass of a higher index of refraction one face of which is in part concaved and filled with spectacle glass, the remaining part of said face and the filled in portion of the spectacle glass being formed with a continuous convex curve substantially complementary 95 to the countersunk recess in the major blank and secured therein.

100 In testimony whereof, we have hereunto subscribed our names this 25th day of September, 1928.

105 EMANUEL KLEIN.
THEODORE SCHQENER.
